RAILWAY-TRAFFIC-CONTROLLING APPARATUS.

Application filed June 10, 1922, Serial No. 567,397. Renewed August 26, 1924.

Our invention relates to railway traffic controlling apparatus of the type wherein traffic governing means located on a car or train is controlled by energy received from the trackway, and the supply of at least a part of such energy from the trackway to the train depends upon traffic conditions in advance of the train. More specifically, the present invention relates to apparatus of this character in which the governing means on the train require the constant supply of energy of the proper characteristics from the trackway to prevent an automatic application of the brakes.

In connection with systems of this nature, it has been proposed to provide apparatus which will cause an automatic application of the brakes when such application should occur, together with means for preventing such application by a suitable action on the part of the engineer, and it has also been proposed to cause an automatic application at a subsequent point if not prevented by a second suitable action on the part of the engineer.

One feature of our invention is the provision of a new and improved means for producing an automatic application at such subsequent point to prevent the train proceeding without retardation if such automatic application is not properly and safely fore stalled by action of the engineer.

We will describe certain forms of apparatus embodying our invention, and will then point out the novel features thereof in claims.

In the accompanying drawing, Fig. 1 is a diagrammatic view showing one form of apparatus embodying our invention, and Fig. 2 is a view showing on an enlarged scale the vehicle carried receiving coils and receiving circuits shown in Fig. 1. Fig. 3 is a view showing a modification of the apparatus shown in Fig. 1 and also embodying our invention.

Similar reference characters refer to similar parts in each of the several views.

Referring first to Fig. 1, the reference characters 1 and 1^a designate the track rails of a railway along which traffic normally moves in the direction indicated by the arrow. These rails are divided, by insulated joints 56, into a plurality of track sections

C—D, D—E, etc., each of which sections is provided with a track circuit comprising a source of current and a track relay. As here shown, the source of current for each track circuit is the secondary 57 of a transformer designated by the reference character T with an exponent corresponding to the location, which secondary is connected with the track rails through a pole-changer as hereinafter explained. The primary 58 of each of these transformers is connected with a transmission line 59 which is constantly supplied with alternating current by a generator 60. The relay for each section is designated by the reference character K with an exponent corresponding to the location, and comprises a winding 61 connected across the track rails of the section, and a co-operating winding 62 constantly supplied with alternating current by the secondary 65 of an adjacent transformer X the primary 58^a of which is connected with the transmission line 59. Each relay includes a contact 63 which occupies an intermediate position when the relay is de-energized and is swung to the right or to the left according as track winding 61 is supplied with current of one instantaneous relative polarity or the other.

Located adjacent the entrance end of each track section is a roadside signal designated by the reference character L with an exponent corresponding to the location. Each of these signals is controlled by the associated track relay K in a usual and well known manner, but inasmuch as the control of the signal has nothing to do with our present invention, we have omitted the controlling circuits from the drawings in order to simplify the disclosure as much as possible. Suffice it to say, that when a track relay is de-energized, the associated signal indicates "stop"; when the track relay is energized by track current of reverse relative polarity (that is, when contact 63 is swung to the left), the signal indicates "caution"; and when the relay is energized by track current of normal relative polarity (that is, when contact 63 is swung to the right), the signal indicates "proceed".

Interposed in each track circuit between the transformer secondary 57 and the track rails is a pole-changer which is designated by the reference character Z with an ex-

ponent corresponding to the location. Each of these pole-changers is operated by the adjacent signal L in such manner that current of normal relative polarity is supplied to the track rails when the signal indicates proceed or caution, and current of reverse relative polarity is supplied to the track rails when the signal indicates stop.

The apparatus thus far referred to is constructed and arranged in accordance with well known principles of railway signaling, and the operation of this portion of the apparatus will be understood without further explanation.

Each track section is further provided with means for supplying line current to the track rails. For this purpose a resistance 68^a is connected across the track rails at the entrance end of the section, a second resistance 68^b is connected across the rails at the exit end of the section, and as shown in Fig. 1, a third resistance 68^c is connected across the rails at approximately maximum braking distance from the exit end of the section. Line current is constantly supplied to the rails of each section between resistances 68^a and 68^b by means of a secondary 67 of the adjacent transformer X, the terminals of which secondary are connected with the middle points of these two resistances, respectively. Line current is also at times supplied to the rails of each section between resistances 68^b and 68^c by a secondary 66 on the adjacent transformer T. One terminal of secondary 66 is constantly connected with the middle point of resistance 68^b, while the other terminal is at times connected with the middle point of resistance 68^c through contact 63 of the track relay K for the section next in advance and also through a contact 64 operated by the signal L for such section next in advance, contact 64 being closed when the signal indicates proceed or caution, and open when the signal indicates stop.

It will be seen from the foregoing, that line current is always supplied to the rear portion of each track section; whereas such current is supplied to the forward portion between resistances 68^b and 68^c when the next section is unoccupied, but not when such section is occupied.

The reference character V designates a railway vehicle, which may be either a car or a train. Mounted on this vehicle (see Fig. 2) in front of the forward axle are two magnetizable cores 69 and 69^a located directly above the track rails 1 and 1^a respectively. The cores 69 and 69^a are provided with windings 73 and 73^a which are connected in a receiving circuit *a* in such manner that the currents induced in these windings by track circuit current from transformer secondaries 57 are cumulative, where- 65 as the currents induced in these windings

by line current from secondaries 66 and 67 are in opposition and therefore create no current in circuit *a*. Also mounted on the vehicle V in a suitable position, such as in the rear of the forward axle, are two other magnetizable cores 70 and 70^a, located directly above the track rails 1 and 1^a; respectively. These cores are provided with windings 173 and 173^a, which are included in a receiving circuit *b* in such manner that the currents induced in these windings by line current in the track rails are cumulative, whereas the currents induced in these windings by track circuit current in the track rails oppose each other and therefore create no current in the circuit *b*.

The reference character A designates a relay carried by the vehicle V, and which we will term the main relay. As here shown, this relay is of the induction motor type, comprising a rotor 2 and two stator windings 3 and 3^a. The windings 3 and 3^a are controlled by the energy created in circuits *a* and *b* respectively, by currents in the track rails. Interposed between the receiving circuit *a* and the relay winding 3 is an amplifying device 71, and interposed between receiving circuit *b* and relay winding 3^a is another amplifying device 72. These amplifying devices may be of any suitable form, and they are not illustrated in detail herein because they form no part of our present invention. The rotor 2 of relay A operates a circuit controlling contact finger 4. The control of relay A is such that when line current is supplied to the receiving circuit *b* and track circuit current of normal relative polarity is supplied to receiving circuit *a*, the contact finger 4 is swung to the right, which we will term the "normal" position, whereas, when the receiving circuit *b* is energized and the receiving circuit *a* is energized by track circuit current of reverse relative polarity the contact finger is swung to the left, which we will term the "reverse" position. When either receiving circuit *a* or *b* is de-energized, the relay A is de-energized, so that its contact finger occupies its vertical position. It will be seen at once from the foregoing that when the vehicle is traveling under a proceed signal, the main relay A is energized in normal direction, and that when the vehicle is traveling under a caution signal this relay will be energized in reverse direction, whereas, after the vehicle passes the resistance 68^b in a caution block, relay A will become de-energized due to the loss of line current.

The main relay A controls a magnet M in such a way that this magnet is energized directly through contact 4 when relay A is energized in normal direction. At such time the circuit for magnet M passes from terminal B of a suitable source of current through contact 4-4^a of relay A, wire 11, 120

magnet M and wire 15 to terminal O of the same source of current. Magnet M is at times energized by virtue of another circuit which will be explained hereinafter.

Magnet M controls a valve 5 in such manner that the movable member of this valve is in its lowest position when the magnet is energized, and in its highest position when the magnet is de-energized. When magnet

10 M is energized the valve 5 connects a reservoir R' with the main reservoir of the braking system through pipes 8 and 8^a. This being the normal position of valve 5, it follows that reservoir R' is normally charged to 15 main reservoir pressure. When the magnet M becomes de-energized the reversal of valve 5 serves to disconnect reservoir R' from the pipe 8^a and to connect this reservoir with the underside of a piston 7 through a pipe 6, the 20 reservoir at the same time being connected with an orifice 9 of restricted area which opens to the atmosphere. Unless prevented by other means, which will be explained hereinafter, the pressure of reservoir R' on 25 the underside of piston 7 causes this piston to move upwardly against the action of a spring 22 and to remain in such position until the pressure in reservoir R' is reduced to a certain value by the exhaust of this pressure through orifice 9. When piston 7 is elevated, it opens a valve 17 which then connects a pipe 13 with atmosphere through an 30 exhaust port 18.

Pipe 13 controls a brake application valve 35 S. The valve S comprises a slide valve 19 governed by a piston 20 which piston is biased to the right by a spring 24. Both sides of the piston 20 are normally exposed to main reservoir pressure through pipes 8 40 and 8^b and a small orifice 20^a in the piston 20. It will be seen, therefore, that as long as pipe 13 is closed the air pressures on the opposite sides of piston 20 are equal so that 45 this piston is held in its right-hand position by the influence of spring 24; slide valve 19 is then in such position that the valve device is inactive in that it does not cause an application of the brakes. When pipe 13 is 50 opened to atmosphere, however, the pressure on the left-hand side of piston 20 is reduced so that this piston and the slide valve 19 are 55 shifted to the left. When this occurs the pipe 8^c, which leads to the engineer's brake valve W and to the left-hand side of feed valve 10, is disconnected from the main reservoir; that is, from pipe 8^b, so that the 60 engineer is unable to release the brakes by manipulation of valve W. The left-hand movement of piston 19 causes an application of the brakes in the following manner:

The exhaust of air from brake pipe 29 is controlled by an auxiliary valve 33 which is attached to a piston 26. The upper surface of piston 26 is normally exposed to brake pipe pressure through pipe 30, chamber 31

and pipe 38, the equalizing reservoir RE, being also exposed to this same pressure through the branch pipe 32. The underside of piston 26 is also exposed to brake pipe pressure but the effective area of this side of the piston is less than that of the upper surface owing to the stem of valve 33, so that the piston normally occupies its lowest position wherein valve 33 is closed. When the slide valve 19 moves to the left, however, the upper side of piston 26 and the equalizing reservoir RE are disconnected from pipe 30 and are connected with a reduction reservoir RR through chamber 31 and pipe 37. The pressure on the upper side of piston 26 is thus reduced by a certain amount so that this piston rises, thereby opening valve 33 and allowing the brake pipe to exhaust to atmosphere. When the brake pipe pressure is reduced to a value lower than the equalized pressure on the upper side of piston 26 this piston again moves downwardly and closes valve 33, thereby preventing a further reduction of pressure in the brake pipe. By proper proportioning of the two reservoirs RE and RR, any desired brake pipe reduction may be secured, such, for example, as a reduction of 20 lbs.

Returning to piston 7 it will be remembered that upon de-energization of magnet M this piston rises and thereby opens pipe 13 to atmosphere, and after an interval of time determined by the exhaust of reservoir R' through orifice 9, this piston returns to its normal position, thereby permitting valve 17 100 to return to its closed position and so to disconnect pipe 13 from atmosphere. Main reservoir pressure then builds up on the left-hand side of piston 20, so that this piston is again shifted to the right, and the slide 105 valve 19 is thus returned to its normal position. The upper side of piston 26 and the equalizing reservoir RE are then again connected with the brake pipe 29 through pipe 38, chamber 31 and pipe 30, whereas the reduction reservoir RR is opened to atmosphere through pipe 37, chamber 39 and exhaust port 40. The brake pipe 29 is then re-charged by main reservoir pressure from pipe 8^b which flows through pipe 8^c, pipe 8^a, 110 feed valve 10, pipe 41, chamber 42 of engineer's valve W, and pipe 43 to brake pipe 29. The parts are thus restored to their normal condition wherein they are ready for a subsequent operation of the brake application 115 valve S.

The foregoing operation of the apparatus controlled by magnet M is the operation that takes place when the vehicle V passes a caution signal unless the engineer takes suitable 125 action to prevent the automatic application of the brakes. To enable the engineer to do this, means are provided for supplying fluid pressure to the upper surface of piston 7 during the time interval in which this 130

piston would otherwise be elevated by the pressure from reservoir R' . The supply of pressure to the upper surface of piston 7 is controlled by a manually operable valve J which is placed in the cab within easy reach of the engineer. When valve J is in the normal position, as shown in the drawing, the upper surface of piston 7 is connected with atmosphere through a pipe 28 and an orifice 21 of restricted area. When the handle of valve J is swung around through 180° , the valve serves to connect a reservoir R^2 with main reservoir through pipes 8^a, 8^b and 8, so that the reservoir R^2 becomes charged to main reservoir pressure. If handle J is then returned to its normal position reservoir R^2 is disconnected from main reservoir and is connected with pipe 28 and also with exhaust orifice 21, so that for a certain time interval, determined by the flow of air through orifice 21, the upper surface of piston 7 is supplied with pressure from reservoir R^2 . The lower side of piston 7 is provided with an annular rib which operates with a gasket in the end of the cylinder in which this piston operates, so that when the piston is down the effective area exposed to reservoir R' is considerably less than that exposed to reservoir R^2 , and so it follows that with equal pressures in both reservoirs the piston will remain at its lowest position. The parts of the apparatus are so proportioned that if valve J is reversed and then restored to its normal position at the time that magnet M becomes de-energized, the piston 7 will be held down by pressure from reservoir R^2 until the pressure in reservoir R' is reduced below the value required to raise the piston. In other words, if the engineer operates the acknowledging valve J at the time that magnet M becomes de-energized he can prevent an automatic application of the brakes.

The vehicle carried apparatus may be provided with an indicator 128 to show the engineer at all times the actual condition of the apparatus. This indicator comprises two pressure gages having pointers 28^a and 90^a. Pointer 28^a is responsive to the pressure in pipe 28 which connects with reservoir R^2 , and pointer 90^a is responsive to the pressure in pipe 90 which connects with reservoir R' . When magnet valve M is energized, the pressure supplied to reservoir R' causes pointer 90^a to move in a clockwise direction, indicating to the engineer that the vehicle is under the protection of the train control system. When magnet valve M is de-energized, the pressure in reservoir R' is slowly dissipated to atmosphere through restricted port 9 and pointer 90^a therefore drifts slowly toward the left. When valve J is in the normal position as shown in the drawing atmospheric pressure exists in reservoir R^2 and pointer 28^a is in its left

hand position. When valve J is reversed however, reservoir R^2 is charged to main reservoir pressure and pointer 28^a is moved to a right hand position. If now valve J is again restored to normal, this pressure is slowly dissipated to atmosphere through port 18 and pointer 28^a drifts toward the left. Complete information is thus given the engineer at all times concerning the operation of the apparatus.

In so far as the apparatus thus far described is concerned, it will be seen that the operation is as follows:

Track section E—F being occupied by a vehicle V', signal L^e indicates stop, signal L^p indicates caution and signal L^c indicates proceed. Vehicle V can therefore proceed through section C—D at full speed, but upon passing signal L^p relay A will become reversely energized due to the fact that the track circuit current in section D—E is of reverse relative polarity. The reversal of relay A will de-energize magnet M, and so if the engineer fails to operate the acknowledging valve J the brakes will be applied and the vehicle will be brought to a stop. On the other hand, if the engineer operates valve J at the moment the vehicle passes point D, that is, just before magnet-operated valve 5 reverses to admit air from reservoir R' to the under side of piston 7, the automatic brake application will be prevented and the vehicle may proceed through section D—E under the control of the engineer.

With the apparatus thus far described, it will be obvious that there is nothing to prevent the engineer from proceeding through section D—E and into section E—F at full speed. It is desirable, however, to prevent such train operation to make sure that the engineer is fully aware that he is approaching a stop signal. To accomplish this we have provided a slow-operating circuit controller Y which is so designed that its contact 12—12^a is normally open, but that this contact closes upon the expiration of a given time interval after the controller becomes energized. This circuit controller may be, for example, similar to the controller shown in United States Letters Patent No.1,272,972, granted to L. V. Lewis on July 16, 1918. This circuit controller is provided with an energizing circuit which includes contact 4—4^b of relay A, and which circuit will be obvious from the drawing. It will be seen, therefore, that this circuit controller is normally de-energized but becomes energized when relay A becomes energized in reverse direction, that is, when the vehicle passes a caution signal. After the circuit controller Y becomes energized an interval of time elapses before contact 12—12^a becomes closed, and upon the expiration of this time interval a new circuit for magnet M be-

- comes closed, which circuit passes from terminal B of a suitable source of current through contact 12-12^a of circuit controller Y, wires 14 and 11, magnet M, and wire 15 to terminal O of the same source of current. The time interval required for the operation of circuit controller Y is at least as great as the time interval required for a full application of the brakes when magnet M becomes de-energized. It will be seen, therefore, that circuit controller Y will not prevent an automatic application of the brakes when the vehicle passes the caution signal L^P.
- 15 The operation of the apparatus in so far as it is affected by the circuit controller Y, is as follows:
- We will assume that when the vehicle V passes signal L^P the engineer operates the acknowledging valve J and thereby prevents an automatic application of the brakes. Circuit controller Y becomes energized at this point and after the expiration of the fixed time interval of this circuit controller magnet M again becomes energized, due to the auxiliary circuit through contact 12-12^a of controller Y. Valve 5 is then restored to its normal position wherein reservoir R' is charged from the main reservoir and so the brake application apparatus is restored to the same condition as that which exists when the vehicle is traveling under a proceed signal. When the vehicle reaches resistance 68^b in section D-E the main relay A becomes de-energized, thereby de-energizing circuit controller Y so that contact 12-12^a opens immediately. This again causes de-energization of magnet M so that unless the engineer takes suitable action the brakes will be applied and the vehicle will be brought to a stop. If, however, the engineer operates the acknowledging valve J in the same manner as before he is able to prevent the automatic application of the brakes, but by so doing he shows that he is aware of the fact that he is approaching a stop signal.
- If desirable, a trackway marker G may be placed at resistance 68^b in each section to indicate to the engineer the location of this resistance.
- With the arrangement of trackway apparatus shown in Fig. 1, it will be seen that when a train is approaching a stop signal the second acknowledgment must be made at location 68^b, which is at some distance in the rear of the stop signal, this distance usually being maximum braking distance for full speed. In some instances, however, it may be desirable to eliminate location 68^b and provide for the second acknowledgment or the second brake application at the stop signal itself. To accomplish this the trackway apparatus shown in Fig. 3 may be employed, which apparatus is identical to that shown in Fig. 1, except that resistance 68^b is omitted from each track section, and the secondary 66 of each transformer T is connected with resistances 68^a and 68^c, which are located at the entrance and exit ends of the section respectively. In other words, line circuit current is always supplied to the rails of each section throughout the entire length of the section.
- If an automatic brake application is incurred, as by failure of the engineer to properly acknowledge a change of traffic conditions, the upward movement of piston 16 uncovers port 13^a and this piston is thereafter held in an intermediate position by the equilibrium between the force exerted by spring 16^a and the unequal pressures on the two sides of piston 16. When the piston is in this position, however, pipe 13 is open to atmosphere through restricted port 18 and the pressure on the left of piston 20 can not build up high enough to reverse valve S and release the brakes. To overcome this difficulty, we provide pipe 13 with a manually operable valve H by means of which the pipe 13 may be opened to atmosphere. When valve H is opened, the decrease in pressure on the under side of piston 16 allows this valve to be moved downward by spring 16^a, thus covering port 13^a. Valve H can now be closed, and pressure builds up on the left hand side of piston 20 and reverses valve S to release the brakes. If valve H is operated while the brakes are released, it will reduce the pressure to the left of piston 20 and apply the brakes.
- The operation of the apparatus shown in Fig. 3, is as follows:
- The vehicle V may proceed through section C-D at full speed, because track circuit current of normal relative polarity is supplied to the rails of this section. Track circuit current of reverse relative polarity is supplied to the rails of section D-E, however, and so as the vehicle passes point D the engineer must operate the acknowledging valve J or an automatic application of the brakes will occur. Assuming that the engineer does operate the acknowledging valve J, the train may proceed through section D-E and circuit controller Y will then be energized. Upon passing point E the circuit controller Y will become de-energized so that an automatic application of the brakes will occur unless the engineer again operates the acknowledging valve J.
- Although we have herein shown and described only two forms of apparatus embodying our invention, it is understood that various changes and modifications may be made therein within the scope of the appended claims without departing from the spirit and scope of our invention.
- Having thus described our invention, what we claim is:
1. Railway traffic controlling apparatus

- comprising a vehicle, provided with a magnet, mechanism on said vehicle controlled by said magnet and effective for a given interval of time after de-energization of the 5 magnet to apply the brakes, manually operable means on the vehicle for preventing an application of the brakes during said interval of time, a three-position relay on said vehicle having normal and reverse contacts, a circuit for said magnet controlled by a normal contact of said relay, a slow-closing electromagnetic circuit controller on the vehicle having a time element at least as great as the time interval of said brake 10 applying mechanism, a circuit for said controller including a reverse contact of said relay, an auxiliary circuit for said magnet governed by said circuit controller; and means partly on the vehicle and partly in 15 the trackway for energizing said relay in normal direction under clear traffic conditions, in reverse direction under caution traffic conditions and for de-energizing the relay under stop conditions.
- 20 2. Railway traffic controlling apparatus comprising a vehicle provided with a magnet, mechanism on said vehicle controlled by said magnet and effective for a given interval of time after de-energization of the magnet to apply the brakes, manually operable means on the vehicle for preventing an application of the brakes during said interval of time, a relay on the vehicle capable of normal and reverse energization, a 25 slow-closing electromagnetic circuit controller on the vehicle having a time interval at least as great as that of said brake-applying mechanism, means for energizing said circuit controller when said relay becomes energized in reverse direction, means for energizing said magnet when said relay is energized in normal direction, other means for energizing said magnet when said circuit controller is closed; and means partly on 30 the vehicle and partly in the trackway for energizing said relay in normal direction under clear traffic conditions, in reverse direction under caution traffic conditions and for de-energizing the relay under stop conditions.
- 35 3. Railway traffic controlling apparatus comprising a vehicle provided with a magnet, mechanism on said vehicle controlled by said magnet and effective for a given interval of time after de-energization of the magnet to apply the brakes, manually operable means on the vehicle for preventing an application of the brakes during said interval of time, a relay on the vehicle capable of normal and reverse energization, a 40 slow-closing electromagnetic circuit controller on the vehicle having a time interval at least as great as that of said brake-applying mechanism, means for energizing said circuit controller when said relay becomes energized in reverse direction, means for energizing said magnet when said relay is energized in normal direction, other means for energizing said magnet when said circuit controller is closed; and means partly on 45 the vehicle and partly in the trackway for energizing said relay in normal direction under clear traffic conditions, in reverse direction under caution traffic conditions and for de-energizing the relay under stop conditions.
- 50 4. Railway traffic controlling apparatus comprising a vehicle provided with a magnet, mechanism on said vehicle controlled by said magnet and effective for a given interval of time after de-energization of the magnet to apply the brakes, manually operable means on the vehicle for preventing an application of the brakes during said interval of time, a slow-closing electromagnetic circuit controller on the vehicle, means for energizing said magnet when said circuit controller is closed; and means partly on the vehicle and partly in the trackway for energizing said magnet directly under clear traffic conditions, for energizing said circuit controller under caution conditions, and for de-energizing both said magnet and circuit controller under stop conditions.
- 55 5. Railway traffic controlling apparatus comprising a vehicle provided with a magnet, mechanism on said vehicle controlled by said magnet and effective for a given interval of time after de-energization of the magnet to apply the brakes, manually operable means on the vehicle for preventing an application of the brakes during said interval of time, means partly on the vehicle and partly in the trackway and operating under clear traffic conditions to energize said magnet, said means operating upon a change to caution condition to de-energize said magnet for a time interval at least as great as the time interval of said mechanism and to then re-energize said magnet, and said means operating under stop conditions to de-energize said magnet and keep it de-energized.
- 60 6. Railway traffic controlling apparatus comprising a trackway divided into sections, a source of alternating current connected across the rails of each section, means for supplying a second alternating current to the rails of each section, means for each section controlled by traffic conditions in advance for reversing the relative polarity of one of said currents, a vehicle; a relay thereon controlled by said currents in the track rails and assuming a normal condition when both currents are present and the reversible current is of normal polarity, a reverse condition when said reversible current is reversed, and a de-energized condition when either current is absent; a magnet on said vehicle, mechanism controlled by said magnet and effective for a given interval of time after the magnet is de-energized to apply the vehicle brakes, manually operable means on

the vehicle for preventing an application of the brakes during said interval, a slow-closing electromagnetic circuit controller on the vehicle having a time interval at least as

5 great as that of said mechanism, a circuit for said controller closed when said relay is in reverse condition, means for energizing said magnet when said relay is in normal condition, and other means for energizing 10 said magnet when said circuit controller is closed.

7. Railway traffic controlling apparatus comprising a stretch of railway track divided into a plurality of successive sections, 15 means for supplying each section with track circuit current and with line current the relative polarity of which currents is controlled in accordance with traffic conditions in advance, vehicle carried governing means including a device effective when actuated to apply the brakes, means for maintaining said device in its ineffective condition when the portion of trackway occupied by the vehicle is supplied with track circuit current and 20 line current the relative polarity of which currents is normal, and means effective upon reversal of the relative polarity of such currents to actuate said device and subsequently return it to its ineffective condition and also 25 effective upon the interruption of either of such currents to again actuate the device.

8. Railway traffic controlling apparatus comprising a vehicle carried relay capable of energization in a normal or a reverse direction, means located partly on the vehicle 30 and partly in the trackway for energizing said relay in one direction under clear traffic conditions and in the other direction under caution traffic conditions but for de- 35 energizing the relay under stop conditions, a device on the vehicle effective when actuated to apply the brakes, and means for maintaining said device in its ineffective condition when said relay is energized in the 40 normal direction but for actuating said device and subsequently restoring it to ineffective condition when the relay becomes energized in the reverse direction and for again actuating the device when the relay becomes 45 de-energized.

9. Railway traffic controlling apparatus comprising a vehicle carried relay capable of energization in a normal or a reverse direction, means located partly on the vehicle 50 and partly in the trackway for energizing said relay in one direction under clear traffic conditions and in the other direction under caution traffic conditions but for de-energizing the relay under stop conditions, a valve 55 on the vehicle arranged when opened to apply the brakes, and means for keeping said valve in its closed position when said relay is energized in the normal direction and for opening said valve and subsequently 60 reclosing it when the relay becomes energized 65

in the reverse direction and for again opening said valve when the relay subsequently becomes de-energized.

10. Railway traffic controlling apparatus comprising a stretch of railway track, a vehicle carried relay capable of energization in a normal or a reverse direction, means partly on the vehicle and partly in the trackway for successively energizing the relay in the normal direction, energizing the relay in the reverse direction, and de-energizing the relay as the vehicle proceeds from safe to dangerous territory, a valve on the vehicle arranged when opened to apply the brakes; and means for keeping said valve in its closed position when said relay is energized in the normal direction, for opening said valve and subsequently reclosing it when the relay becomes energized in the reverse direction, and for again opening said valve when the relay subsequently becomes de-energized.

11. Railway traffic controlling apparatus comprising a stretch of railway track, a railway vehicle, a valve on the vehicle arranged when opened to apply the brakes, and means partly on the train and partly in the trackway to successively open, close and reopen said valve as the vehicle approaches another vehicle ahead, said means including line current constantly supplied to the track rails and track circuit current also constantly supplied to the track rails but controlled as to relative polarity by traffic conditions in advance.

12. Railway traffic controlling apparatus comprising a vehicle provided with a magnet, mechanism on said vehicle controlled by said magnet and effective to apply the brakes, a slow closing electromagnetic circuit controller on the vehicle, means for energizing said magnet when said circuit controller is closed, and means partly on the vehicle and partly in the trackway for energizing said magnet under clear traffic conditions and for energizing said circuit controller under caution conditions and for de-energizing both said magnet and said circuit controller under stop conditions.

13. Railway traffic controlling apparatus comprising a vehicle provided with a magnet, mechanism on said vehicle controlled by said magnet and effective for a given interval of time after de-energization of the magnet to apply the brakes, a slow closing electromagnetic circuit controller on the vehicle, means for energizing said magnet when said circuit controller is closed; and means partly on the vehicle and partly in the trackway for energizing said magnet under clear traffic conditions, for energizing said circuit controller under caution conditions, and for de-energizing both said magnet and said circuit controller under stop conditions.

14. Railway traffic controlling apparatus comprising a vehicle provided with a normally energized magnet, mechanism on said vehicle controlled by said magnet and effective for a given interval of time after de-energization of the magnet to apply the brakes, and means partly on the vehicle and partly in the trackway and operating upon a change from clear to caution traffic conditions to de-energize said magnet for at least the time interval of said mechanism and to then re-energize said magnet, said means operating under stop conditions to again de-energize said magnet. 70
15. Railway traffic controlling apparatus comprising a vehicle carried relay capable of energization in a normal or a reverse direction, means located partly on the vehicle and partly in the trackway for energizing said relay in one direction under clear traffic conditions and in the other direction under caution traffic conditions but for de-energizing the relay under stop conditions, a valve on the vehicle arranged when opened to apply the brakes, means for keeping said valve in its closed position when said relay is energized in the normal direction but for opening said valve when said relay is energized in the reverse direction or is de-energized, and manually operable means on the vehicle effective for a time interval to prevent opening of said valve when said relay is energized in reverse direction or is de-energized. 75
16. Railway traffic controlling apparatus comprising a stretch of railway track, a railway vehicle, a valve on the vehicle arranged when opened to apply the brakes, manually operable means on the vehicle effective for an interval of time to prevent application of the brakes when said valve is opened, and means partly on the train and partly in the trackway to successively open, close and reopen said valve as the vehicle approaches another vehicle ahead. 80
17. Railway traffic controlling apparatus comprising a vehicle provided with a magnet, mechanism on said vehicle controlled by said magnet and effective for a given interval of time after de-energization of the magnet to apply the brakes, manually operable means on the vehicle for preventing an application of the brakes during such interval of time, a slow closing electromagnetic circuit controller on the vehicle, means for energizing said magnet when said circuit controller is closed; and means partly on the vehicle and partly in the trackway for energizing said magnet under clear traffic conditions, for energizing said circuit controller under caution conditions, and for de-energizing both said magnet and said circuit controller under stop conditions. 85
18. Railway traffic controlling apparatus comprising a vehicle provided with a normally energized magnet, mechanism on said vehicle controlled by said magnet and effective for a given interval of time after de-energization of the magnet to apply the brakes, manually operable means on the vehicle for preventing an application of the brakes during such interval of time, means partly on the vehicle and partly in the trackway operating upon a change from clear to caution traffic conditions to de-energize said magnet for at least the time interval of said mechanism and to then re-energize said magnet, and said means operating under stop conditions to again de-energize said magnet. 90
19. In combination, a railway track divided into sections, means for supplying line current to the rails of each section throughout the length of the section regardless of traffic conditions in advance of the section, means for supplying the rails of each section with track circuit current of normal or reverse relative polarity according to traffic conditions in advance of the section, a vehicle carried relay controlled by said track rail currents and responsive to reversals of relative polarity of the track circuit current, and governing means on the vehicle controlled by said relay. 95
20. In combination, a stretch of railway track, means for constantly supplying said stretch with line current throughout its length, means for supplying said stretch with track circuit current of normal or reverse polarity according as traffic conditions in advance are safe or dangerous respectively, and train carried brake controlling apparatus responsive to said two trackway currents and controlled in accordance with the relative polarity thereof, regardless of the speed of the train. 100
21. In combination, a stretch of railway track, means for constantly supplying said stretch with line current throughout its length, means for supplying said stretch with track circuit current of normal or reverse polarity according as traffic conditions in advance are safe or dangerous respectively, and train carried governing means controlled by said two trackway currents and arranged to apply the brakes regardless of the speed of the train when the relative polarity of said track circuit current is reversed. 105
22. In combination, a railway track divided into sections, means for supplying line current to the rails of each section throughout the length of the section regardless of traffic conditions in advance of the section, means for supplying the rails of each section with track circuit current of normal or reverse relative polarity according to traffic conditions in advance of the section, and train carried governing means controlled by said track currents and 110

responsive to reversals of the relative polarity thereof.

23. In combination, a railway track divided into sections, means for supplying each section throughout its length with line current regardless of traffic conditions in advance and with track circuit current, the relative polarities of which currents are normal or reverse depending on traffic conditions in advance of the section, train carried relay controlled by said currents and responsive to reversals of relative polarity thereof as well as to cessation of either current, means for causing a brake application when said relay becomes energized in reverse direction and also when said relay becomes de-energized, and manually operable means on the train for preventing said brake applications.

24. In combination, a railway track divided into sections, means for supplying each section throughout its length with line

current regardless of traffic conditions in advance and with track circuit current, the relative polarities of which currents are normal or reverse depending on traffic conditions in advance of the section, a train carried relay controlled by said currents and responsive to reversals of relative polarity thereof as well as to cessation of either current, means for causing a brake application when said relay becomes energized in reverse direction and also when said relay becomes de-energized, and manually operable means on the train for preventing said brake applications.

In testimony whereof we affix our signatures.

HENRY W. GRIFFIN.
LEMUEL F. HOWARD.
